UNITED STATES PATENT OFFICE.

NAPOLEON DU BRUL, OF CINCINNATI, OHIO.

WEIGHING-SCALE.

SPECIFICATION forming part of Letters Patent No. 299,758, dated June 3, 1884.

Application filed January 25, 1884. (No model.)

To all whom it may concern:

Be it known that I, NAPOLEON DU BRUL, of Cincinnati, in the county of Hamilton and State of Ohio, have invented a new and useful 5 Improvement in Weighing-Scales, of which the following is a specification.

My invention relates to improvements in those balance or weighing scales in which the torsional elasticity of metal or analogous material is employed to control the oscillations of the beam.

My improvements have for their object the production, at a moderate expense, of a torsion-balance of great sensitiveness and durability and of simple and cheap construction.

In another application, No. 118,691, I have shown, described and claimed, and applied to one form of scale a flat torsion strip, bar, or rod stretched horizontally and set up 20 edgewise, to form a fulcrum strip, bar, or rod for the beam. In other applications, Nos. 118,693, 118,694, 118,695, and 118,979, I have shown and described the employment of such torsion strip, bar, or rod with other forms of 25 scales. The present form of my invention has the beam extending in both directions, one end of the beam supporting a pan for the articles to be weighed, and the other end being graduated for a sliding weight.

30 In the accompanying drawings, Figure 1 is a perspective view of a weighing-scale embodying my present invention. Figs. 2 and 3 are respectively a vertical and a horizontal section of the same.

35 A is a base or foot, upon which are two posts, B, in which slots b in pairs, one pair vertically above the other pair, receive the ends of torsion strips, bars, or rods C C', of steel or equivalent elastic material. These strips, 40 bars, or rods, having been tightly stretched, are firmly secured in their respective slots by any suitable means, preferably by means of a screw, E, passing through a clamping-block, D. The posts B are the fulcrum-posts, and 45 the strips, bars, or rods the fulcrum strips, bars, or rods. To each fulcrum strip, bar, or rod, at or near its mid-length, there is attached, by similar clamping blocks and screws to those mentioned, a scale-beam, F, and a connecting- 50 bar, F', respectively, the scale-beam extending on both sides of the fulcrum strip, bar, or rod, for support on the respective sides of the

weighing-pan and one or more sliding weights, as hereinafter explained. Each beam or bar F F' terminates on the pan side of the machine in a T-head or cross-bar, G, to whose outturned lips g are fastened, by clamping block and screw, as above, the ends of two stretched torsion strips, bars, or rods, H, similar to the fulcrum strips, bars, or rods already 60 spoken of. To these strips, bars, or rods H, at their mid-lengths, is directly and rigidly fastened the pan-support J of the pan K. The portion of the beam F on the side of the fulcrum strip, bar, or rod C remote from the pan 65 is marked with a scale, L, and carries one or more sliding weights, M. The stem J, being prolonged downward, as shown, by its contact with the base, limits the oscillations of the beam occasioned by weight put in the pan. 70

The object of the combination of the beam or bar F and the torsion strip, bar, or rod secured thereto is to fasten the end of the pan-support in a perfectly vertical, and the weighing-pan consequently in a constant horizontal, position under every oscillation of the beam, which is of great importance in a 75 weighing-scale.

The torsion strips, bars, or rods are in the present illustration shown as flat strips of 80 metal having proper elasticity and flexibility to twist when the scale is oscillating; but I do not confine myself to this special form of bar, as any other shape of stretched strip, bar, or rod having the proper elasticity and 85 applied in the manner shown will accomplish the purpose. My scale is furthermore susceptible of other modifications without departure from the characteristic features of the invention. For example, there may be two 90 vertical pan-supports, to which the ends of the torsion strips, bars, or rods H may be fastened, and the beam and bar ends be fastened at mid-lengths of said torsion strips, bars, or rods. The fulcrum-posts of the beams and bars 95 might be branched out to be fastened to the ends of the fulcrum strips, bars, or rods C C', while they could twist on a single post from the base fastened to the center of the torsion strips, bars, or rods. Knife-edge fulcrum-pivots could be used in place of fulcrum strips, bars, or rods C C', while the pan-support could be fastened to torsional strips, bars, or rods 100 H, as shown.

I claim as new and of my invention—

1. In a weighing-scale, the combination of fulcrum torsion strips, bars, or rods, scale-beam, connecting-bar, sliding weight on the scale-beam on one side of the fulcrum, torsion strips, bars, or rods secured rigidly and directly to the pan ends of the scale-beam and connecting-bar on the other side of the fulcrum, and a pan-support rigidly and directly secured to the end torsion strips, bars, or rods, substantially as set forth.
2. In a weighing-scale, the combination of

pivoted weight-beam, short connecting-bar, base, and a pan-support rigidly and directly attached to torsion strips, bars, or rods rigidly and directly attached to the outer ends of the weight-beam and connecting-bar, substantially as set forth. 15

In testimony of which invention I hereunto set my hand.

NAPOLEON DU BRUL.
